Primary Examiner — Terry Wallace*(74) Attorney, Agent, or Firm* — Boyle Fredrickson, S.C.(57) **CLAIM**

The ornamental design for a sifting scoop, as shown and described.

DESCRIPTION

FIG. 1 is a perspective view of a sifting scoop incorporating our new design, viewed from in front of, above, and from the right side thereof;

FIG. 2 is a front elevation view thereof;

FIG. 3 is a right side elevation view thereof;

FIG. 4 is a rear elevation view thereof;

FIG. 5 is a left side elevation view thereof;

FIG. 6 is a top plan view thereof; and,

FIG. 7 is a bottom plan view thereof.

The dashed lines in FIGS. 1-7 are for illustrative purposes only and form no part of the claimed design.
